BOWLING ALLEY

Dana B. Hinckley, Brookline, Mass.

Application May 10, 1939, Serial No. 272,857

4 Claims. (Cl. 273—50)

Among the objects of the present invention are the provision of automatic foul line signals responsive to the body capacity of a bowler.

Another object of the present invention is the 5 enclosure of a pair of automatic capacity foul line signals within a single metal box in such manner that the actuating circuits are not subject to interaction upon each other.

Figure 1 is a perspective view of a pair of 10 bowling alleys showing the foul line detectors in place.

Figure 2 is a wiring diagram showing the actuating circuits for a pair of foul line detectors.

Figure 3 is enlarged detail view showing the 15 relation of the antenna to the bowling alley surface.

The present invention relates to electrical means for indicating violation of the foul lines in bowling alleys. More particularly, the invention 20 relates to the use and special adoption of a so-called "capacity relay" circuit for use as a foul line indicator in bowling alleys. A single unit of the device consists of a three element vacuum tube 10 in conjunction with suitably fixed 25 condensers, C₁, C₂, C₃ and C₄, a variable condenser C₅, a radio frequency choke coil 11 and a relay 12, the same connected to an antenna 13 which for this particular use is integral with the 30 foul line strip 14. The operation of the capacity relay circuit is such that when the bowler slides his foot over the foul line, or passes it slightly above the foul line, the capacity of the grid circuit of the vacuum tube is thereby affected—as the antenna is connected directly to the tube 35 grid—causing the tube to go into a state of oscillation. This state of oscillation in turn causes an increased flow of current through the plate circuit, in which the relay coil is connected in series. The increased flow of current in the relay coil 40 serves to close the relay contacts 15 thus completing an external circuit and causing a light 19 to be turned on, and a gong to be sounded, or both.

The light may be placed directly on the box 16 45 containing the relay apparatus, or in any other convenient location.

The box 16 should be located as near the foul line as is reasonably possible, a convenient location being just under the ball returns 17.

50 Connections with the relay box for the 110 volt and 6 volt circuits are established through a standard conduit (not shown). The antenna leads 18 are brought in separately through individual holes in the bottom of the box.

55 Each circuit is adjusted by means of the varia-

ble condenser C₅ to a point at which the tube 10 is near a state of oscillation. To make this adjustment correctly, a person should stand with one foot just over the foul line, at which time the capacity of C₅ should be decreased until the 5 tube goes into oscillation, causing the above described effect.

Up to the present time, it has been impractical to use more than one "capacity relay" circuit within a single enclosed metal box, for the reason 10 that the circuits are subject to interaction of one upon the other. This effect manifests itself in that when one circuit goes into a state of oscillation, because of the addition of capacity to its antenna, the other circuit is also likely to start 15 oscillating, which would obviously be confusing as it would turn on the foul indicating lights for two alleys.

After some study the cause of this interaction has been discovered and also its remedy. The 20 cause is due to the fact that as a result of quantity production in these units, they are naturally made of identical parts. This in turn brings about operation on the same frequencies. Each 25 circuit is subject to interference—through inductance or capacity or feed back through the power lines on the frequency to which it is tuned.

Now, the factor in the operation of these units which causes the relay to function is the increased flow of current through the relay coil 30 when the tube oscillates. For example, if the tube passes a current of 1.50 milliamperes when set by C₅ to the required degree of sensitivity, it may pass 3.00 milliamperes when in a state of 35 oscillation. Now since the relay contacts 15 will close with a current flow of say 2.1 milliamperes, this increase in current flow from 1.5 mils to 3 mils will cause it to operate. Now again this increase in current flow in one circuit induces an added current flow in the adjacent circuit which is sufficient to bring the current in that plate 40 circuit from 1.50 mils up to 2.1 mils (since the circuit characteristics are identical)—which in turn causes the other relay circuit to operate.

To remedy this state of affairs, it is necessary 45 that the circuits A and B—which are adjacent in the same box—should be made to operate on different frequencies, in which case they will not be sensitive to changes in current flow, each to the other.

50 Since the frequency of oscillation is controlled by the combination of the choke coil 11 and the capacity C₄ it follows that a change in either of these values will change the frequency of oscillation of the circuit of which it is a part.

Hence it is only necessary for satisfactory operation of two of these circuits in close proximity to each other, to make the capacities C_4 of different values, thus causing the aforesaid difference in operating frequencies of the two circuits.

However, the difference of frequencies must be such that there is no mathematical relation between them. That is, there must be no common denominator to the different frequencies on which the two operate—For example—if circuit A operates on 4 megacycles and circuit B on 6 megacycles there is a common denominator of 2 megacycles. Now these circuits, when in oscillation will set up harmonics on other frequencies than those on which they are oscillating, these harmonics being multiples of some denominator of each. The circuits also are sensitive to induced currents on these harmonics. Therefore, it follows that A, operating on 4 megacycles may set up harmonics and 2 or/and 6 megacycles which will be picked up by B or vice versa thus causing increased current flow in the plate circuits of the other unit and the consequent operation of its relay.

This difficulty may be overcome by arranging the capacities C_4 so that there will be no common denominator to the frequencies of oscillation of the 2 circuits. For example circuit A may be made to operate on 4 megacycles and B on 5 megacycles. While there will be a common multiple of 20 megacycles for these two frequencies, this seems to be sufficiently far out of range so that it does not affect the satisfactory operation of the two units.

The units are arranged two in a metal box, which is placed below the rise in the ball returns, each unit caring for the foul line on one alley.

40 The wiring is carried out in such a way that the warning lights 19 will stay on until turned out by breaking the contact at a hand controlled switch 21. These switches must be in the 115 volt feed lines 23 to the units, which may be either DC or AC and not in the 6 volt lines 25 which supply the tube heater current, as if placed in this latter circuit the tube filaments would be allowed to cool each time the control switch 21 was used to turn out a light 19. This would be undesirable as the tube heaters require an appreciable time to reach a stable operating temperature.

While the foul line indicator will operate satisfactorily with the antenna strip installed as in A, in any position from the horizontal to the vertical position, improved operation is noted when the installation is made as indicated in Fig. 3. This angle is about 30° from the horizontal.

60 I claim:

1. A device for indicating when a player passes over the foul line in a bowling alley comprising a radio frequency circuit having an antenna positioned along a line adjacent the foul line, said radio frequency circuit having a plate circuit ar-

ranged to have an increased current flow when the capacity of the grid circuit is affected by the player's foot passing over the foul line, an alarm circuit, electrical means operatively associated with said plate circuit and said alarm circuit and adapted to be actuated to close said alarm circuit in response to said increased current flow, said antenna being in the form of a flat metal strip positioned below the surface of the alley and forming an acute angle therewith.

2. A device for indicating when a player passes over the foul line in a bowling alley comprising a radio frequency circuit having an antenna positioned along a line adjacent the foul line, said radio frequency circuit having a plate circuit arranged to have an increased current flow when the capacity of the grid circuit is affected by the player's foot passing over the foul line, an alarm circuit, electrical means operatively associated with said plate circuit and said alarm circuit and adapted to be actuated to close said alarm circuit in response to said increased current flow, said antenna being in the form of a flat metal strip positioned below the surface of the alley and forming an acute angle therewith.

3. In a bowling alley having two adjacent playing lanes, electrical means for indicating when a player passes over the foul line in either lane comprising a pair of radio frequency circuits one having an antenna positioned along a line adjacent the foul line of one lane and the other having an antenna positioned along a line adjacent the foul line of the other lane, each of said radio frequency circuits having a plate circuit arranged to have an increased current flow when the capacity of its grid circuit is affected by the player's foot passing over the foul line, a pair of alarm circuits, electrical means operatively associated with said plate circuits and alarm circuits and adapted to be actuated to close an alarm circuit in response to said increased current flow, and means for causing said radio frequency circuits to operate at different frequencies of oscillation.

4. In a bowling alley having two adjacent playing lanes, electrical means for indicating when a player passes over the foul line in either lane comprising a pair of radio frequency circuits one having an antenna positioned along a line adjacent the foul line of one lane and the other having an antenna positioned along a line adjacent the foul line of the other lane, each of said radio frequency circuits having a plate circuit arranged to have an increased current flow when the capacity of its grid circuit is affected by the player's foot passing over the foul line, a pair of alarm circuits, electrical means operatively associated with said plate circuits and alarm circuits and adapted to be actuated to close an alarm circuit in response to said increased current flow, and a fixed capacity in each of said radio frequency circuits for causing said circuits to operate at different frequencies of oscillation.

DANA B. HINCKLEY.
